UNITED STATES PATENT OFFICE.

HARRY HARDWICK, OF PHILADELPHIA, PENNSYLVANIA, ASSIGNOR TO THE IVINS, DIETZ & METZGER COMPANY, OF SAME PLACE.

WOVEN FABRIC AND MODE OF WEAVING SAME.

SPECIFICATION forming part of Letters Patent No. 629,292, dated July 18, 1899.

Application filed February 7, 1899. Serial No. 704,829. (No specimens.)

To all whom it may concern:

Be it known that I, HARRY HARDWICK, a citizen of the United States, residing in Philadelphia, Pennsylvania, have invented Improvements in Woven Fabrics and Mode of Weaving the Same, of which the following is a specification.

My invention consists of a fabric woven in one piece and having throughout some parts or parts of its length a less number of warp-threads than in another part or other parts of its length, the invention also comprising a method of dropping out and reintroducing the warp-threads without materially complicating or delaying the weaving operation.

In the accompanying drawings, Figure 1 is an exaggerated longitudinal section on the line of the warp of a cut pile fabric made in accordance with my invention. Fig. 2 is a transverse section on the line *xx*, Fig. 1. Fig. 3 is a transverse section on the line *ww*, Fig. 1. Fig. 4 is a view similar to Fig. 1, but illustrating a special form of fabric made in accordance with my invention. Fig. 5 is a sectional view of another form of fabric embodying the invention. Figs. 6 to 10 are diagrams illustrating the mode of weaving the fabric, and Fig. 11 is a side view of part of a separator-bar which I prefer to employ in carrying out my invention.

In Fig. 1 the portion of the fabric marked 1 may represent the center or body portion of a woven rug, and the portions marked 2 may represent the end or border portions of said rug. In a fabric of the character shown the pattern or pile is formed by the warp-threads, and it is frequently desirable to employ in the borders patterns of a much more elaborate character and requiring a greater number of colors than the pattern of the center or body portion of the rug. For instance, there may be as many as eight different threads in each set of warps required for the borders, while one, two, or three warps may be sufficient for the body portion. Hitherto in weaving this class of fabrics it has been generally considered necessary to employ full sets of warp-threads throughout the entire length of the fabric, the warp-threads which were not employed in forming the pattern in the body of the fabric being buried at the back of the same. It is this waste of expensive warp-threads which it is the object of my invention

to overcome, and I accomplish this object by discontinuing the patterning warp-threads throughout that portion of the fabric in which they are not required in the formation of the pattern. Thus, supposing a fabric to be divided transversely into successive sections, some of these sections will have a greater number of patterning warp-threads than others. For instance, the sections 2 of the fabric shown in Fig. 1 each contain patterning warp-threads 3 in sets of eight, while in the section 1 of the fabric five of the warp-threads 3 have been dropped from each set, the remaining three threads being all that are necessary for the production of the desired body pattern. There are also binding warp-threads 4 in pairs alternating with the sets of patterning warp-threads and binding weft-threads 5, the latter being disposed in sets of three each, forming the well-known three-shot binder used in weaving pile fabrics.

In dropping a warp-thread from the fabric it is preferably carried up into the pile, or if it be a cut pile into one of the tufts, so that it will be in position above the fabric, where it is accessible for being cut off, although if the fabric is woven upside down—that is to say, with the pile-wires on the under side of the warp-threads instead of above the same—the dropped warp-threads may be cut off on the back of the fabric and not carried into the pile, the back of the fabric in this case being the part which is uppermost in weaving, and consequently the part which is accessible for the purpose of cutting out the warp-threads desired to be dropped.

Any desired backing-warp may be used in the fabric as in an ordinary pile fabric.

In the fabric shown in Fig. 4 a heavy jute warp-thread 6 is used in the body portion of the fabric to take the place of the patterning warp-threads which have been dropped, so that the fabric will have substantially uniform thickness throughout, and such thread may be used in place of or in addition to ordinary backing warp-threads.

In Fig. 5 I have shown my invention as applied to what is commonly termed a "damask" carpet fabric, in which the pattern is formed by warp-threads 3^a, inclosing stuffer-wefts 7, the warps being tied down between these stuffer-wefts by means of wefts 8. In this case the superfluous warp-threads 3^a are cut

off abruptly at the line of junction of the body and border on the back of the fabric. The method of weaving the fabric shown in Figs. 1, 2, and 3 is illustrated in Figs. 6 to 10 of the drawings and is as follows: In these figures 10 represents the lay of the loom; 11, a spiked take-up roll occupying the position of the usual breast-beam; 12, a yarn-spool; 13, a guide-wire, over which the patterning warp-threads pass, and 14 a weight hung in a bight of each patterning warp-thread between the spool 12 and guide-wire 13. The patterning warp-threads are controlled by harnesses 15 and the binding warp-threads by harnesses or heddles 16. The fabric is woven as usual until a border is completed, whereupon the harnesses controlling the patterning warp-threads which are to be dropped are raised, as shown in Fig. 6, so that said threads are out of action, and they are held in this position during the weaving of the body portion of the fabric, which continues with the remaining patterning warp-threads. After the weaving of the body of the fabric with a limited number of patterning warp-threads has continued for a number of picks a notched bar 17, such as shown in Fig. 11, is inserted horizontally beneath the raised warps, as shown by dotted lines in Fig. 7, and then raised up to a vertical position, and thus retained by suitable supports, as shown by full lines in said Fig. 7, so as to collect the warp-threads in bunches at the bases of the V-shaped notches of the bar, this operation at the same time separating the bunches of threads, so that the weaver can observe the operation of weaving which is being carried on below them. During the time that the border of the fabric is under control of the spiked take-up roll 11 the raised and inoperative patterning warp-threads will be drawn forward with the fabric, the weights 14 being lifted as the slack of the threads between the spools 12 and guide-wires 13 is taken up; but after the border portion of the fabric has passed beyond the control of the spiked take-up roll 11, as shown in Fig. 8, the strain upon the raised or inactive warp-threads tends to pull the free portion of the fabric back over the portion which is being woven and carried forward by the take-up roll, and this operation will be continued until the folding back of the woven fabric is arrested by contact of the same with the notched bar 17, as shown in Fig. 9, or until the strain upon the raised warp-threads is relieved by the weights 14 reaching in their descent a suitable support. As the weaving of the body portion of the fabric proceeds a loop of such fabric is formed, depending from the take-up roller 11, and this loop of fabric may be held under any desired degree of tension by the insertion of a rod or bar 18—as shown in Fig. 9, for instance. When the desired length of body fabric has been woven, the bar 17 is removed, so that the border portion of the fabric can be drawn forward to

the beating-up point, as shown in Fig. 10, and the inactive harnesses 15 are then drawn into action again, so as to proceed with the weaving of another border portion of the fabric, until the entire number of patterning warp-threads which were held out of action during the weaving of the body portion of the fabric have been woven into the fabric again, whereupon the connection between those portions of the warp-threads contained in the newly-woven border and the portions contained in the previously-woven border may be cut and the folded portion of the web thus released, or the entire piece may be woven before cutting the connections between the patterning warp-threads in successive border portions of the fabric.

One of the main advantages of my invention is that it provides for the dropping out and reintroduction of patterning warp-threads without any material change in or addition to the ordinary loom and without requiring any special skill on the part of the weaver or material lessening of the production of the loom, while the saving of the expensive patterning warp-threads throughout all that portion of the fabric in which their presence is not required very materially cheapens the product without any corresponding lessening of its marketable value, since the durability of the fabric is not dependent upon the number of threads which lie buried in the backing, but more upon the durability of the pile-surface, which is not materially affected by my improved method of weaving the fabric.

I have shown my invention as applied to the weaving of a cut pile fabric, the pile-wires 20 being so formed as to cut the loops formed over them as they are withdrawn from the fabric, and the notched bar 17, being inserted at the point where the pile-wires are withdrawn, serves the additional function of raising the inactive patterning warp-threads above the pile-wires, so that said threads will not be cut by the pile-wire as it is withdrawn. It will be observed on reference to Fig. 1 that wherever a patterning warp-thread is dropped from the fabric it is carried to the face and appears in a pile-tuft, and, if desired, the single strand of yarn formed by thus raising the patterning-warp may constitute the pile-tuft at that point instead of a double strand formed by looping the pile-warp around the pile-wire, or the pile-thread which is to be put out of operation may be raised with the thread which is to form the pile-loop at that point, in which case the thread which is to be put out of action will add to the bulk of pile-tuft at the point where it is raised.

In an uncut pile fabric or even in a cut pile fabric the upstanding ends of the cut warp-threads which have been dropped from the fabric may, if desired, be cut out of the fabric after the completion of the same, and instead of raising the pile-threads individually to put them out of action at different points in the fabric the whole body of warp-threads

which is to be dropped may be lifted simultaneously at the line of junction of the border and body of the pattern and may be introduced bodily in the same way.

5 In producing the fabric with the stuffer warp-thread 6 in the body portion, as shown in Fig. 4, said stuffer warp-thread may be controlled by a special heddle and introduced continuously during the weaving of the fabric, being allowed to remain down continuously during the weaving of the border portions of the fabric, so as to float on the back of the fabric throughout these border portions, whereby it can afterward be conveniently cut off, or it may be woven into the border portion of the fabric, if so desired.

In producing the damask fabric (shown in Fig. 5) the upside-down method of weaving before referred to is preferably adopted, so that the patterning warp-threads not used in the body of the fabric will extend from one border portion to the other folded-back portion on the back of the fabric which in this case is uppermost in the loom and can be severed without being carried to the face or under side of the fabric, where in a fabric of this character their presence might be objectionable.

In cases where the discarded warp-threads are wound on beams instead of spools the fabric may be drawn forward by the take-up mechanism until the entire length of fabric with the lesser number of warp-threads has been woven, whereupon the folding back of the fabric may be effected by a backward turning of said warp-beams until the previously-woven portion of the fabric containing all of the warp-threads has been drawn back to the beating-up point to permit the discarded warp-threads to be again introduced into the fabric.

While it will doubtless be preferable in most if not in all cases to drop out of action certain warp-threads of each set, complete sets of warp-threads may without departing from my invention be dropped out of action in order to obtain the desired result. Thus alternate sets of the warp-threads or one set in three may be thus dropped out.

50 My invention in its broadest embodiment is not limited to patterned fabrics in which the warp-threads form the pattern, as it can be adopted in weaving plain fabrics in which a greater bulk or thickness is needed in some parts than in others.

Having thus described my invention, I claim and desire to secure by Letters Patent—

1. A fabric woven in one piece, with a pattern formed by the warp-threads, and having some of said patterning warp-threads extending throughout the entire length of the fabric, and others discontinued throughout part of the length of the fabric.

2. A fabric woven in one piece with warp-threads in sets and having some of the threads of each of the sets extending throughout the entire length of the fabric, and others discon-

tinued throughout part of the length of the fabric.

3. A fabric woven in one piece, with pattern formed by the warp-threads, and having some of said patterning warp-threads extending throughout the entire length of the fabric, and others discontinued throughout part of the length of the fabric, and replaced by an independent thread or threads which is discontinued throughout those portions of the fabric where the full number of patterning warp-threads is employed.

4. A pile fabric woven in one piece with pattern formed by the pile-threads, and having some of said pile-threads discontinued throughout part of the length of the fabric, each pile-thread, before being discontinued, passing to the face of the fabric.

5. A cut pile fabric woven in one piece, with patterns formed by the pile-threads, and having some of the pile-threads discontinued throughout part of the length of the fabric, each pile-thread before being discontinued, passing to the face of the fabric and uniting with other pile-threads to form pile-tufts, substantially as specified.

6. The mode herein described of weaving a fabric having a greater number of warp-threads in one portion of its length than in another, said mode consisting in moving and maintaining out of action the surplus warp-threads during the weaving of that portion of the fabric having the lesser number of warp-threads, folding the fabric back upon itself so as to bring that portion of the fabric from which the threads were removed up to the last-woven portion of the fabric containing the lesser number of warp-threads, reintroducing the inoperative warp-threads into the fabric, and severing said threads where they pass from one portion of the fabric to the other, substantially as specified.

7. The mode herein described of weaving a fabric having a greater number of warp-threads in one portion of its length than in another, said mode consisting in moving and maintaining out of action the surplus warp-threads, laterally separating into groups said inoperative warp-threads, and holding them thus separated during the weaving of that portion of the fabric having the lesser number of warp-threads, folding the fabric back upon itself so as to bring that portion of the fabric from which the threads were removed up to the last-woven portion of the fabric containing the lesser number of warp-threads, reintroducing the inoperative threads into the fabric, and severing said threads where they pass from one portion of the fabric to the other, substantially as specified.

In testimony whereof I have signed my name to this specification in the presence of two subscribing witnesses.

HARRY HARDWICK.
